VACUUM CLEANER NOZZLE

Johan Arne Dömstedt, Hagersten, and Christian Staffans-
son Klingspor, Stockholm, Sweden, assignors to Aktie-
bolaget Electrolux, Stockholm, Sweden

Filed June 1, 1971, Ser. No. 149,090

Term of patent 14 years

Int. Cl. D15—05

U.S. Cl. D7—174

FIG. 1

FIG. 2

FIG. 3

FIG. 4

FIG. 5

FIG. 6

FIG. 7

FIG. 1 is a front perspective view of a vacuum cleaner nozzle showing our design;

FIG. 2 is a rear perspective view with the nozzle inverted from the position shown in FIG. 1;

FIG. 3 is a side elevational view with the nozzle in the position shown in FIG. 1;

FIGS. 4 and 5 are front and rear elevational views, respectively, with the nozzle in the position shown in FIGS. 1 and 3;

FIG. 6 is a plan view from above with the nozzle in the position shown in FIGS. 1, 3, 4 and 5; and

FIG. 7 is a plan view from above with the nozzle in the position shown in FIG. 2.

We claim:

The ornamental design for a vacuum cleaner nozzle, as shown.
